UNITED STATES PATENT OFFICE.

PINGREE H. MCKAY, OF BAY CITY, MICHIGAN.

SANITARY FACE SHIELD.

Application filed September 9, 1926. Serial No. 134,410.

This invention relates to sanitary face pads, and particularly to a pad to cover the frame in which the patient's face is placed when the eyes are being tested.

5 The prime object of the the invention is to design a sanitary pad, which can be quickly applied to and removed from the frame, and which completely protects the patient's face from contact with any part 10 of the said frame.

Another object is to design a pad provided with integral strips for holding it in position, together with a projecting section adapted to cover the adjustable chin rest.

15 A further object is to provide a simple and convenient pad which is easy to make, and which can be packed in bundles or cartons for shipment and distribution.

The above and other objects will appear 20 as the specification progresses, reference being had to the accompanying drawing in which I have shown the preferred embodiment of my invention, and in which like reference numerals indicate like parts 25 throughout the several views thereof.

In the drawing:

Fig. 1 is a front view of the pad formed to shape.

Fig. 2 is a front view of the frame showing my sanitary pad in place thereon.

Fig. 3 is an edge view thereof.

Fig. 4 is a sectional view of the adjustable chin rest, and

Fig. 5 is an enlarged transverse sectional 35 plan view of one of the side bars of the frame illustrating the pad covering.

Where a large number of people must place their face in the same identical frame, a sanitary problem is immediately present, 40 due to the fact that in warm weather the patients perspire freely, and when the frame is damp, dust and foreign matter will adhere thereto, and no patient cares to thrust his or her face into a frame on which the perspiration from another patient's face has 45 been deposited, even though it is wiped clean with a cloth each time.

In cold weather the frame is cold making it disagreeable at this time of the year, and 50 I have therefore designed a sanitary pad which completely covers the frame and allows for adjustment of the chin rest, eliminating contact of the patient's face there-

with, and which can be discarded and a fresh pad used for each patient.

55 Referring now particularly to the drawing, the numeral 5 indicates the frame or face rest of a conventional optical machine, such as used by eye examiners for testing the eyes. This is mounted on a post 6, and 60 a chin rest 7 is adjustably mounted in said post, projecting therefrom as clearly shown in Figs. 2 and 3 of the drawings.

The pad comprises a sheet of paper or similar material 8, shaped to cover the edges 65 of the frame as clearly shown in Fig. 1 of the drawing, and having a centrally disposed opening 9 to accommodate the patient's face, a small lip 10 being formed on the upper end, and an opening 11 is punched 70 therein, and through which the pin 12 is inserted for securing the pad in place.

The lower end is formed with a rounded section 13 adapted to cover and fit in the adjustable chin rest 7, and in which the 75 patient's chin rests. Strips 14 and 14^a form a part of the pad, and are used for securing the lower end of the pad in position, the inner edges being cut away as shown at 15 to allow the operator to wrap them around 80 the rib 16, which is formed integral with the chin rest, for holding the bottom of the pad in position.

This pad can be formed from a thin sheet 85 of absorbent paper or other suitable material, and may be moulded or pressed to shape, I find however that it is economical to shape it from a flat sheet, leaving sufficient stock to cover the frame, and when the patient's face is inserted, the pad easily conforms to the contour thereof, and I do not wish to be limited to any specific manner or method of forming the pad.

90 In practice the patient is seated in the chair used for the purpose, the operator 95 raises the member 12, places the top of the pad so that the pin engages the opening 11, holding the upper end of the pad in position, he then grasps the strips 14 and 14^a crossing them around the rib 16, the opening 100 15 permitting this winding action, and the pad is in position. After the test is completed, it is removed and a new pad attached, the fact that the chin rest projects at an angle to the frame permits of the vertical adjustment thereof without affecting the pad,

as any excess stock is taken up in this bend.

From the foregoing description it will be obvious that I have perfected a very simple, and economical sanitary pad for optical ma-
5 chines and the like.

What I claim is:—

1. A sanitary pad formed of flexible ma-
terial, and having a centrally disposed opening and a rounded lower section of a size
10 to permit it to be pressed into and cover the chin rest of an eye testing machine and
means integral with the pad for securing
it in position.

2. The combination with an eye testing
15 machine having a head rest or frame, of a
sanitary pad adapted to cover said frame
and formed with a centrally disposed opening,
a rounded lower section adapted to cover
the chin rest, and means for securing said
20 pad in position.

3. The combination with an eye testing
machine having a head rest or frame, of a
sanitary pad provided with a centrally dis-
posed opening, the marginal edges of which
cover said frame, a rounded section below
said opening adapted to cover the chin rest,
and strips on the edges of said opening for
securing the pad in position.

4. The combination with an eye testing
machine having a head and chin rest, of a
sanitary pad provided with a centrally dis-
posed opening, the marginal edges of which
cover said frame, a rounded section below
said opening for covering said chin rest, a
lip on the upper end of the pad, and strips
35 on the edges of said opening adapted to be
wound on the chin rest for securing said
pad in position.

In testimony whereof I affix my signature.

PINGREE H. MCKAY.
